Attys.

UNITED STATES PATENT OFFICE.

JOHN OUELLETTE, OF NEW BEDFORD, MASSACHUSETTS.

STOP MECHANISM FOR LOOMS.

1,394,341.

Specification of Letters Patent. Patented Oct. 18, 1921.

Application filed June 30, 1919. Serial No. 307,591.

To all whom it may concern:

Be it known that I, JOHN OUELLETTE, a citizen of the United States, residing at New Bedford, in the county of Bristol and State of Massachusetts, have invented new and useful Improvements in Stop Mechanism for Looms, of which the following is a specification.

This invention relates to stop mechanism for looms and has as its object the provision of a device which will automatically apply the loom brake and stop the operation of the picker motion under certain undesirable and defective positions of the shuttles.

The device is primarily intended for use with a loom having opposite shuttle boxes and may be used with a loom of this character which is provided with a shuttle box or boxes at each end of the race way.

It is well known in the art to provide stop mechanism for looms which operate when the shuttle boxes at each end of the lay are full and stop the loom in order to prevent smashing of the shuttle upon the race way or in one of the boxes. It is for this purpose that my invention is intended and as showing a device of the character to which my invention relates, attention is called to the patent to Shanahan, 482,930, September 20, 1892. My device comprising a construction somewhat similar to the structure shown in the above mentioned patent, but intended to be an improvement thereon.

One object of my invention is the provision of a device of the character described which is extremely simple in construction, by reason of having a minimum number of parts; which because of its simplicity is adaptable to any loom and may be readily applied without in any way changing the construction of the loom. The above and other objects of my invention will become more obvious as the description proceeds, reference being had to the accompanying drawings, in which:

Figure 1 represents the lay of a loom, showing my stop mechanism applied thereto, the breast beam being removed so as to more clearly disclose the structure of the stop mechanism.

Fig. 2 is a vertical cross-sectional view of a loom taken on the line $x-x$ of Fig. 1, the breast beam and the remainder of my stop mechanism being shown in this view.

Fig. 3 is an elevational view of the slide bar of the brake operating mechanism.

Fig. 4 is a similar view of the supporting bracket for the slide bar, and

Fig. 5 is a detail view of the member for returning the dagger or kicker to inoperative position.

In the several views A indicates the lay, B the breast beam, and S the shuttle boxes of a loom which in the present instance is of the drop-box type. Adjacent the lay is the usual protector rod P which extends entirely across the lay provided with the customary binder fingers F at each end thereof. This much of the construction shown in the drawings is old and well known in the art, and has been shown in order to illustrate the application of my stop mechanism to a loom and the relation of the mechanism to the working parts of the loom.

Attached to the lay A, and having bearings in bearing brackets 3 are rock shafts 1, 2, each rock shaft being provided with detector fingers 4 held against the shuttle box on a line with the race way in a position to be engaged by the shuttle therein. Each of the rock shafts is at its inner end bent at an angle to the main portion of the shaft and again in a plane parallel with the axis of the shaft in order to form arms 5 positioned against a dagger or kicker 6 freely pivoted upon the protector rod P.

The rock shafts are yieldingly held with their detector fingers against their respective shuttle boxes and their arms 5 against kicker 6 by contractile springs 7 secured at one end of the lay and at their other end to collars 8 adjustably mounted upon the rock shafts. It will be noted that by adjusting the collars around the rock shafts, the tension of the springs may be varied so that as the springs become worn, they may be adjusted to maintain the detector fingers in proper position. It should also be observed that by employing this means for holding the detector fingers against their shuttle boxes and the arms 5 against the kicker, the same may be replaced independently of the rock shafts when it becomes desirable to renew this part of the mechanism upon which there is a great deal of wear.

As above stated, the kicker is freely pivoted for oscillatory movement upon the protector rod P, the protector rod passing through

an opening in the central portion of the kicker. The kicker should be so constructed that it may be applied to the protector rod without removing the latter from the loom. As shown in the springs, a plate 5' is inserted in a recess in a central portion of the kicker opposite the opening for the protector rod to hold the kicker upon the protector rod, and pins 5'' are passed through the main portion of the kicker and the plate 5' to hold the latter in its recess. The protector rod opening is thus closed, and the kicker is free to oscillate about the protector rod. As will be observed from an inspection of Fig. 2, the kicker 6 is provided with an upwardly extending arm 6' adapted to be engaged by the arms 5 of the rock shafts and also has a downwardly extending arm 6'' disposed at an angle to the upper arm and having a lip 9 at its lower end. The kicker is shown in operative position in Fig. 2 and is urged to this position by means of an expansible leaf spring 10 abutting the lay A at one end and the upwardly extending arm 6' of the kicker at its other end. As will be clear upon a reading of the above in connection with the drawing the kicker may be urged to the position shown in full lines in Fig. 2 by its spring 10 only when the arms 5 of the rock shafts have been urged backwardly by the pressure of the shuttles against the detector fingers 4. When there are shuttles in the boxes on a line with the race way at each end of the lay, both of the rock shafts are moved in opposition to their springs 7 and the arms 5 moved from contact with the kicker whereupon the spring 10 moves the kicker to the position shown in full lines in Fig. 2.

With the kicker in the position shown in Fig. 2 (the lay being shown at the end of its forward or beat-up motion), the lip 9 is adapted to engage and actuate the stop or brake operating mechanism upon the backward motion of the lay. The brake operating mechanism will now be described.

Secured to the breast beam B is a bracket having a vertical arm 11, directly attached to the breast beam, and a horizontal arm 12 located below the kicker, the arm 12 being provided with a slide bar 13 whose rabbeted end 14 has a bearing in an eye 15 upon the bracket arm 12 and is further supported for reciprocable movement upon the bracket by means of a pin 16 on the bracket arm 12 passing through a slot 17 in the slide bar. The bar is held in the position shown in Fig. 2 by means of a contractile spring 18 secured at 18' to the bracket, and at 18'' to the slide bar. The vertical arm 11 of the bracket at a medial point has extending therefrom a slotted arm 19 to which is pivotally secured a lever 20 by means of a pin 21, the lever being pivotally secured to the slide bar by means of pin and slot connec-

tion 22, 23. The end of the lever above the fulcrum point 21 has a pin 24 which serves to connect the lever to the usual brake mechanism (not shown) of the loom.

When there are shuttles in the boxes at each end of the lay race way, the detector fingers and arms 5 are pressed outwardly permitting the spring 10 to urge the kicker 6 about the protection rod from the dotted line position shown in Fig. 2, to the full line position shown therein. After the lay starts its backward motion, the lip 9 upon the kicker engages a shoulder 25 upon the slide bar and continued backward movement of the lay serves to retract the slide bar in opposition to the tension of the spring 18 causing a pivotal movement of the lever 20 about its fulcrum 21 and the application of the loom brake, thus stopping the picker motion of the loom.

Means is provided for automatically returning the kicker 6 to its inoperative position shown in dotted lines in Fig. 2, the means comprising a bar 26 inclined downwardly in the direction of the breast-beam, the forward end 26' of which engages the lip 9 of the kicker upon resumption of the picker motion of the loom after the defect causing operation of the stop mechanism has been remedied. Continued backward movement of the lay causes the kicker to travel along the bar resulting in pivotal movement of the kicker back to inoperative position. The bar 26 may be secured to the bracket arm 12 in any suitable manner but in the present instance it is shown as being attached thereto by means of a portion 26'' bent from the bar and extending downwardly to engage a pin 28 upon the opposite side of the arm 12 from that shown in the drawing. It should be clear that after the kicker is urged back by the bar 26 to inoperative position, the rock shafts 2 are turned by their spring 7, the arms 5 thereby following the kicker 6 to its inoperative position.

It is thought that the operation of my mechanism will be clear from the above description, the operation having been described during the course of the delineation of the mechanical construction. It should be understood that I do not limit myself to the identical construction shown in the accompanying views, the structure shown therein being but one embodiment of my invention as defined in the following claims:

1. In a stop mechanism for looms, the combination with a loom provided with a lay having opposite shuttle boxes and the usual protector rod extending entirely across the lay, of rock shafts on the lay having detector fingers adjacent the shuttle boxes, arms on said shafts, a loom stop, mechanism for operating the stop, and means for actuating the operating mechanism comprising

a kicker freely mounted for pivotal movement upon said protector rod, and means urging said kicker into position to engage the stop operating mechanism, the arms on 5 said rock shafts being normally positioned in the path of said kicker and holding the same in inoperative position.

2. In a stop mechanism for looms having a lay with opposite shuttle boxes and the 10 usual protector rod extending entirely across the lay, the combination of a pair of rock shafts each having a detector finger adapted to be positioned adjacent the shuttle boxes, a kicker adapted to be positioned for free pivotal movement upon the protector rod, stop 15 operating mechanism adapted to be mounted upon the breast beam adjacent the kicker, and means urging the kicker into position to engage the stop operating mechanism, said 20 means moving the kicker only when there are shuttles in boxes at opposite ends of the raceway.

3. In a stop mechanism for looms having a lay with opposite shuttle boxes and the 25 usual protector rod extending entirely across the lay, the combination of a pair of rock shafts each having a detector finger adapted to be positioned adjacent the shuttle boxes, a kicker adapted to be positioned for free pivotal movement upon the protector rod without removing the latter, stop operating 30 mechanism adapted to be mounted upon the breast beam adjacent the kicker, and means urging the kicker into position to engage the stop operating mechanism, said means mov- 35

ing the kicker only when there are shuttles in boxes at opposite ends of the raceway.

4. In a stop mechanism as specified in 40 claim 1, means for returning the kicker to inoperative position.

5. In a stop mechanism as specified in 45 claim 2, means for returning the kicker to inoperative position, said means being operable upon the backward motion of the lay.

6. In a stop mechanism as specified in 50 claim 2, spring means for retaining the detector fingers against the shuttle boxes, said spring means being removable and adjustable independently of the rock shafts.

7. In a stop mechanism for looms having 55 a lay with opposite shuttle boxes, rock shafts, detector fingers on the rock shafts positioned adjacent the shuttle boxes, stop operating mechanism on the breast beam, means for actuating said stop operating 60 mechanism comprising a dagger located adjacent the ends of the rock shafts, arms on the rock shafts adjacent said dagger and normally maintaining said dagger in inoperative position, and spring means for retaining 65 the detector fingers adjacent the shuttle boxes, and said arms in the path of said dagger, said means being removable and adjustable independently of the rock shafts.

In testimony whereof I have hereunto set 65 my hand in presence of a subscribing witness.

JOHN OUELLETTE.

Witness:

Jos. Z. BOUCHER.
